UNITED STATES PATENT OFFICE.

WILLIAM REES EVANS, OF YOUNGSTOWN, OHIO.

WHEEL-GUARD.

No. 885,030.

Specification of Letters Patent.

Patented April 21, 1908.

Application filed February 25, 1908. Serial No. 417,735.

To all whom it may concern:

Be it known that I, WILLIAM R. EVANS, a citizen of the United States, residing at Youngstown, in the county of Mahoning and 5 State of Ohio, have invented a new and useful Wheel-Guard, of which the following is a specification.

This invention relates to wheel guards, and more particularly to those adapted for 10 use with railway cars and engine wheels. In most devices of this kind heretofore in use, the parts have been heavy and clumsy, and in addition to adding extra weight, were at the same time expensive to manufacture. 15 The present invention aims to remedy this defect by reducing the number of parts and rendering the device applicable to any truck, and at the same time to produce such a simple structure that it will be comparatively 20 inexpensive to manufacture.

With these and other objects in view, as will more fully hereinafter appear, the invention consists in certain novel features of construction and arrangement of parts, 25 hereinafter fully described, illustrated in the accompanying drawings, and particularly pointed out in the appended claims, it being understood that various changes in the form, proportions, size and minor details of the 30 structure may be made without departing from the spirit or sacrificing any of the advantages of the invention.

In the accompanying drawings:—Figure 1 is a side view, showing the device mounted 35 on the trucks of a street railway car, steam engine, or railway passenger car. Fig. 2 is an end view taken on the line 2—2 of Fig. 1. Fig. 3 is a perspective view of the device.

Similar numerals of reference are employed to indicate corresponding parts 40 throughout the several figures of the drawings.

A fender or guard 1 of approximately triangular form is designed to be arranged in 45 advance of the wheels and supported at a slight distance above the rails 3 by the brackets 4, each bracket being preferably formed of a single piece of steel of a length sufficient to permit its being bent so as to form a front 50 wall 5 the approximate height of the truck, and the arms 6 extending at right angles to the wall 5 and adapted to be secured by bolts 7 on the top and bottom sides of the truck 8 on the outer face of each wheel and to 55 project a slight distance in advance of each

wheel, so as to support the guard 1 as shown in Fig. 1. The outer face 9 of each guard extends upwardly and rearwardly beyond the diameter of the wheels 2 and is of a width sufficient to exceed the thickness of the wheel and is designed to lie adjacent the track but at a distance to clear the same, thereby positively preventing an object on the track from getting between the track and wheel. The advantage of constructing the outer face 60 of the guard on an incline will be readily seen when the device is applied to freight cars and the like which are more or less drilled in the yards, and where it frequently happens that those conducting such drill movements lose 65 either life or limb. With the use of the present device all such accidents will be avoided, since the outer face 9 coming in contact with the leg or arm will lift the same clear of the 70 track and swerve it aside.

The inner face 10 is curved to conform to the configuration of the wheel and designed to be held out of contact with the same, its lower end lying in a plane with the lower end 75 of the wall 9 and substantially tangent to the wheel 2. The lower face 11 of the guard is arched, and at its juncture with the outer face 9 is rounded off, thereby presenting a smooth round surface free from sharp and cutting edges which would inflict injury.

The outer wall of each guard is provided with a vertical groove extending the length 80 of the wall which forms a reception for the front wall 5 of the bracket and is secured to the latter by means of bolts or the like. This 85 construction renders it possible to adjust the guard any desired height above the track, which will be found very advantageous in attaching the device to various sizes of trucks.

What is claimed is:—

1. A wheel guard comprising a body provided with a longitudinal groove, inclined front and rear faces, and a curved lower face, the front end of which adjoining the front 100 face of the guard is rounded, and a means fitted in the groove for supporting said guard adjacent to a wheel and rail.

2. A wheel guard provided with front, rear and lower faces, a bracket secured to a 105 truck having parallel arms and adapted to support the guard adjacent to a wheel and rail.

3. A wheel guard provided with front, rear and lower faces, a bracket having parallel 110

arms secured to a truck on the outer side of a wheel, and adapted to support the guard adjacent to a wheel and rail.

4. A wheel guard provided with front, rear and lower faces, a bracket having parallel arms secured to the upper and lower side of the truck on the outer face of a wheel, and adapted to support a guard adjacent to a wheel and rail.

5. A wheel guard provided with inclined front and rear faces, a curved lower face, a bracket having parallel arms secured to the upper and lower sides of the truck on the outer face of the wheel and adapted to support the guard adjacent to a wheel and rail.

10. 5. A wheel guard provided with inclined front and rear faces, a curved lower face, a bracket having parallel arms secured to the upper and lower sides of the truck on the outer face of the wheel and adapted to support the guard adjacent to a wheel and rail.

15. 5. A wheel guard provided with inclined front and rear faces, a curved lower face, a bracket having parallel arms secured to the upper and lower sides of the truck on the outer face of the wheel and adapted to support the guard adjacent to a wheel and rail.

6. A wheel guard provided with inclined front and rear faces, and a curved lower face, the front end of which adjoining the front face of the guard is rounded, a bracket having parallel arms secured to the upper and 20 lower sides of the truck on the outer face of the wheel and adapted to support the guard adjacent to a wheel and rail.

In testimony that I claim the foregoing as my own, I have hereto affixed my signature 25 in the presence of two witnesses.

WILLIAM REES EVANS.
